CATCH FOR LUGGAGE OR THE LIKE

Lazlo Bako, Woodcliff Lake, N.J., assignor to Walter
Kidde & Company, Inc., East Paterson, N.J.

Filed July 26, 1971, Ser. No. 166,331

Term of patent 14 years

Int. Cl. D8—07

U.S. Cl. 8—129

FIG. 1

FIG. 2

FIG. 3

FIG. 4

FIG. 5

FIG. 1 is a front view of a catch for luggage or the like showing my new design;

FIG. 2 is a side view looking from the right of FIG. 1, the opposite side being a mirror image of the side shown;

FIG. 3 is a rear view;

FIG. 4 is a view looking from the top of FIG. 1; and

FIG. 5 is a view looking from the bottom of FIG. 1. I claim:

The ornamental design for a catch for luggage or the like, as shown and described.
